(57) **CLAIM**

An ornamental design for a vehicle rear bumper cover, as shown and described.

DESCRIPTION

FIG. 1 is a top plan view of a vehicle rear bumper cover;

FIG. 2 is a bottom plan view of the vehicle rear bumper cover;

FIG. 3 is a front elevational view of the vehicle rear bumper cover;

FIG. 4 is a left side elevational view of the vehicle rear bumper cover;

FIG. 5 is a right side elevational view of the vehicle rear bumper cover; and,

FIG. 6 is a perspective view of the vehicle rear bumper cover. The broken lines and surface members shown in faded lighter tones and enclosed in broken lines are for illustrative purpose only and form no part of the claimed design.
